[57] CLAIM

The ornamental design for a novelty cap or similar article, substantially as shown and described.

DESCRIPTION

FIG. 1 is a perspective view of a novelty cap or similar article showing my new design;

FIG. 2 is a top plan view thereof;

FIG. 3 is a right side elevational view, the left side being a mirror image thereof;

FIG. 4 is a front elevational view thereof;

FIG. 5 is a rear elevational view thereof;

FIG. 6 is a bottom plan view thereof;

FIG. 7 is a perspective view of a modified form of the novelty cap or similar article shown in FIG. 1;

FIG. 8 is a top plan view thereof;

FIG. 9 is a right side elevational view, the left side being a mirror image thereof;

FIG. 10 is a front elevational view thereof;

FIG. 11 is a rear elevational view thereof; and

FIG. 12 is a bottom plan view thereof.
